UNITED STATES PATENT OFFICE

154,943

DESIGN FOR A COMBINATION PAPER DISPENSER AND SPICE CONTAINER HOLDER

William E. Mell, Chicago, Ill., assignor to Mell-Hoffmann Mfg. Co., Chicago, Ill., a corporation of Delaware

Application December 17, 1947, Serial No. 143,178

Term of patent 7 years

(Cl. D4—3)

To all whom it may concern:

Be it known that I, William E. Mell, a citizen of the United States, residing at Chicago, Cook County, Illinois, have invented a new, original, and ornamental Design for a Combination Paper Dispenser and Spice Container Holder, of which the following is a specification, reference being had to the accompanying drawing, forming a part thereof.

Fig. 1 is a perspective view of a combination paper dispenser and spice container holder showing my new design; and

Fig. 2 is a perspective view of the device with the cover partially opened.

I claim:

The ornamental design for a combination paper dispenser and spice container holder, substantially as shown.

WILLIAM E. MELL.
